UNITED STATES PATENT OFFICE.

JOHN McFETHRIES, OF SPRINGFIELD, MASSACHUSETTS.

BEARING-SUPPORT FOR LOOM-LAYS.

SPECIFICATION forming part of Letters Patent No. 769,487, dated September 6, 1904.

Application filed May 23, 1904. Serial No. 209,149. (No model.)

To all whom it may concern:

Be it known that I, JOHN McFETHRIES, a citizen of the United States of America, and a resident of Springfield, in the county of Hampden 5 and State of Massachusetts, have invented certain new and useful Improvements in Bearing-Supports for Loom-Lays, of which the following is a full, clear, and exact description.

This invention relates to lay-supports for 10 looms; and it has for its objects the improved construction of such support admitting of perfect freedom of pivotal movement without requiring lubrication, and hence being effective in saving of labor and expense to keep the device 15 in proper working condition.

My improvement is especially adapted to 20 looms in which the lay has a comparatively extensive movement and is supported from a point above the weft in order to reduce the angular movement of the lay-swords without 25 reducing the movement of the reed longitudinally of the warp. It is of course evident that in such an organization the swords may be considerably longer than they could be if the lay was supported at a point beneath the weft. Whereas the overhead support possesses 30 many other desirable features—as, for instance, freedom of access to the weft and the other operative devices of the machine— more or less trouble is necessarily met in keeping the overhead support of the lay properly oiled; and my invention has for its particular purpose the provision of a lay-support in which 35 all lubrication may be entirely dispensed with and substantially in the manner illustrated in in the accompanying drawings, in which—

Figure 1 is a side view of a lay mechanism embodying my invention. Fig. 2 is a front view thereof. Fig. 3 represents a section on 40 line 3 3, Fig. 1; and Fig. 4 is a perspective view of one of the lay-carrying members in detail.

In the drawings, 10 denotes the side frames of a loom.

45 11 is the lay, having the reed 12 and movable longitudinally of the warp-weft 13, as operated by a cam 14 or otherwise from the lay-shaft 15. The lay 11 is secured at its ends to the swords 16, extending upward and united

50 at their upper ends by a girth 17. Attached to the outer side of the swords, near the upper extremities thereof, are plates 20, having lateral projections 21, the lower portions of which are formed to constitute knife-edges 22, adapted to rest in either of the series of 55 notches 23 provided therefor in the upper face of the stationary side frames 10. Means are provided to prevent the knife-edges from accidental displacement relative to the particular notches constituting the supporting 60 faces, these means consisting substantially of an arch 24, secured to each side frame 10, and the inner or lower face 25' of which is concentric with the knife-edge support, the outer and upper face 21' of which is rounded correspondingly, it being of course understood that 65 a small clearance is left between the faces 21' and 25' to prevent rubbing contact between them.

Both lay-swords 16 are simultaneously operated 70 through connecting-links 26, actuated by similar cams 14, and so as to cause both lay ends to move exactly alike and to maintain the reed at a right angle relative to the weft 14.

From the foregoing it is evident that the 75 pivot-point 16' has a uniform swinging movement, and inasmuch as it is desirable to adjust or regulate the position to which the reed shall “beat up” I provide a series of supporting 80 notches 23 in the upper faces of the side frames, both series being alined and finished simultaneously and when the side frames are bored for the shaft 15.

It will now be seen that the lay or reed 12 must necessarily be in parallelism with the 85 axis of the shaft 15 and, furthermore, that when the knife-edges 22 are moved into the front notches 23 the reed 12 will be moved slightly rearward or that when the knife-edges 22 are placed into the rear notches 23 90 the reed 12 will be slightly advanced without disarranging the parallelism of the reed with its original position. When the knife-edges are shifted into different notches, as above described, the retaining-arches 25 must also 95 be shifted correspondingly by withdrawing bolts 30 and passing the same through the proper holes 31, as will be readily understood.

Having thus described my invention, what I claim, and desire to secure by Letters Patent, is—

1. A lay-support comprising a pair of knife-edges, notched members coöperative therewith, and means independent of the swords for retaining the knife-edges in the notches.

2. The combination with a lay, a pair of lay-swords and a pair of knife-edges carried thereby, of a pair of stationary members having notches, and means independent of the swords for retaining the knife-edges in the notches.

3. The combination with a lay, a pair of lay-swords and a pair of knife-edges carried thereby, of a pair of stationary members, each having a series of alined notches for varying the beating-up point of the lay, shiftable devices for retaining the knife-edges in the

notches, and means for positioning said devices relatively to said notches.

4. The combination with a lay, a pair of lay-swords, and a pair of knife-edges carried thereby, of a pair of side frames, a pair of stationary members carried thereby, and each having a series of alined notches for supporting said knife-edges, and for varying the beating-up point of the lay, shiftable arches for retaining the knife-edges in the notches, and means for positioning said arches into concentric position relative to said notches.

Signed by me at Springfield, Massachusetts, in presence of two subscribing witnesses.

JOHN McFETHRIES.
